UNITED STATES PATENT OFFICE.

THOMAS DANQUARD, OF NEW YORK, N. Y., ASSIGNOR TO THE AUTO PNEUMATIC ACTION COMPANY, OF NEW YORK, N. Y., A CORPORATION OF NEW YORK.

EXPRESSION DEVICE FOR AUTOMATIC MUSICAL INSTRUMENTS.

1,413,832.

Specification of Letters Patent. Patented Apr. 25, 1922.

Application filed February 4, 1916, Serial No. 76,077. Renewed July 19, 1921. Serial No. 485,849.

To all whom it may concern:

Be it known that I, THOMAS DANQUARD, a citizen of the United States, residing at New York, in the county of New York and State 5 of New York, have invented a new and useful Expression Device for Automatic Musical Instruments, of which the following is a specification.

This invention relates to an expression device for automatic musical instruments, of the type in which a tracker bar and perforated note-sheet are used.

On such sheets it has been customary to provide indications showing the correct expression or intensity of tone for different parts of the musical composition reproduced on the sheet. For this purpose letters and other characters have been used and the expression has also been indicated by a continuous irregular line running lengthwise of the sheet, and showing by its lateral position the desired strength or intensity of expression. All such indicia, however, merely assist the operator in his manipulation of 25 the instrument and have no tangible or mechanical connection therewith.

Devices have also been constructed by the use of which the expression could be varied automatically, such devices being commonly 30 operated or controlled by pneumatic mechanism connected to one or more special openings in the tracker bar which cooperate with special perforations in the note sheet.

It is the general object of my invention to 35 provide an improved tension regulator of this type, by which the air tension in an automatic musical instrument may be varied automatically, and also to provide improved means for controlling such regulator from 40 the note-sheet.

One feature of my invention relates to the provision of improved devices for retaining the tension regulator in adjusted position, thereby avoiding the use of long 45 perforations or slots in the note sheet, and to the provision of means for automatically releasing said devices prior to or coincident with the adjustment of the tension regulator to a different position.

50 Further features of my invention relate to certain arrangements and combinations of parts which will be hereinafter described and more particularly pointed out in the appended claims.

55 A preferred form of my invention and a

modification thereof are shown in the drawings in which

Fig. 1 is a diagrammatic elevation of my improved expression device and certain parts of the instrument associated therewith; 60

Fig. 2 is a vertical sectional view of the tension regulator, taken along the line 2—2 in Fig. 3;

Fig. 3 is a longitudinal sectional view of the tension regulator, taken along the line 65 3—3 in Fig. 2;

Fig. 4 is a longitudinal sectional elevation of the setting device which controls the tension regulator, the section being taken along the line 4—4 in Fig. 5; 70

Fig. 5 is a plan view of the setting device, partly in section, taken on the line 5—5 in Fig. 6;

Fig. 6 is a transverse sectional elevation of the setting device, taken on the line 6—6 75 of Fig. 5;

Fig. 7 is a plan view of a modified form of setting device;

Fig. 8 is a longitudinal sectional elevation thereof, taken on the line 8—8 of Fig. 80 7, and

Figs. 9 and 10 are transverse sectional elevations of the modified form taken on the lines 9—9 and 10—10 of Fig. 7, respectively.

In Fig. 1 I have shown the general relative position of the several parts of my invention, the tension regulator being designated as a whole by the letter R, the setting device by the letter S and the tracker bar by the letter T. 85

The tension regulator shown in the drawings is of the general type shown and fully described in my prior application Serial No. 865,026, filed October 5, 1914. In the form shown in my prior application, however, no provision is made for automatic setting of the tension regulator and the provision of such automatic setting devices in an improved form constitutes a very important feature of my present invention. 90

Referring to Figs. 2 and 3, I have shown a box or casing 10, divided by a partition 11 into two air chambers 12 and 13. The chamber 13 is directly connected by a passage 15 and pipe 15^a to the exhaust of the instrument, while the chamber 12 is provided with a passage 14 which forms an inlet for the pipe 14^a leading from the pneumatics which operate the actions of the instrument. The chambers 12 and 13 are connected by a port 105 110

16 extending through the partition 11 and normally open as shown in Fig. 2. A tension valve 17 is pivoted at 18 to the partition 11 and is adapted to be swung 5 across the port 16, thereby closing the passage between the chambers 12 and 13 to a greater or less extent, and correspondingly decreasing or increasing the air tension in the chamber 12. The tension valve 17 is 10 adjustably connected by a link 20 to a cross-bar 21 which is rigidly secured to the movable leaves of three pneumatic bellows 22, 23 and 24, mounted in fixed relation to the casing 10 and connectively constituting what 15 may be termed a "pneumatic motor" for selectively positioning the valve 17. The movable leaves of the three bellows and the crossbar 21 carried thereby are normally maintained in raised position by a spring 25 20 mounted upon arms 26 and 27 secured respectively to the movable and to the fixed leaves of the bellows.

The low tension chamber 12 is connected by a passage 30 to a second low tension 25 chamber 31 formed in a casing 32 secured to and rigidly connecting the fixed leaves of the bellows 22, 23 and 24. In the side walls 32^a of the casing 32, a series of valve chambers 33, 34 and 35 are provided, each of these 30 chambers being directly connected to the interior of one of the bellows 22, 23 and 24. A passage 33^a connects the valve chamber 33 to the bellows 22 (Fig. 2) and similar 35 passages, not shown, connect the valve chambers 34 and 35 to the bellows 23 and 24 respectively.

The valve chamber 33 is provided with two ports 33^b and 33^c, the port 33^b being 40 open to the atmosphere and the port 33^c communicating with the low tension chamber 31. The latter port is formed in a cup-like member 36 secured to the frame member 32^a and forming the inner side of the valve chamber. A double valve 37 is mounted to 45 slide axially in said chamber and to close one or the other of said ports, according to its position.

The valve 37 is provided with a head 38 positioned for engagement with a diaphragm 39 forming a so-called pouch and covering a recess 40 formed in the wall 32^b of the casing 32. A pipe or tube 41 leads from the recess 40 and is connected at its opposite end with a setting device to be hereinafter described. For the present it is 55 merely necessary to state that the setting device comprises means for normally closing the tube 41 and for opening the same to the atmosphere under predetermined conditions.

60 A bleed opening 42 connects the recess 40 to the low tension chamber 31, thus normally maintaining equal low tension upon both sides of the diaphragm 39. The valve chambers 34 and 35 are provided with 65 valves, pouches, and controlling tubes pre-

cisely similar in construction and operation to those just described and a detailed description thereof is considered unnecessary. The tube which controls the valve mounted in the chamber 34 is marked 43 and the corresponding tube for the chamber 35 is marked 44.

As above stated, the tubes 41, 43 and 44 are normally closed and the bleed openings maintain equal low tension upon both sides of the diaphragms controlled thereby, the diaphragms being thus rendered inactive. The low tension in the chamber 31 normally draws the double valve 37 against the port 33^c in the cap 36, this closing communication 70 between the valve chamber 33 and the low tension chamber 31. At the same time the uncovering of the port 33^b opens the valve chamber to the atmosphere. The valves in the chambers 34 and 35 are similarly 75 arranged and positioned. Each bellows 22, 23 and 24 is thus exposed to atmospheric pressure within and without and the movable leaves will be raised by the spring 25.

Assuming now that the setting device 80 opens the tube 41 to the atmosphere, the diaphragm 39 will then be exposed to atmospheric pressure upon its right-hand side and to low tension or exhaust pressure upon its left-hand side, as viewed in Fig. 2. The 85 diaphragm will consequently move inward, engaging the head 38 of the valve 37 and moving the valve to open the port 33^b and to close the port 33^c.

The bellows 22 is thus connected through 90 the passage 33^a and the valve chamber 33 to the low tension chamber 31, causing deflation of the bellows 22 to a certain extent against the tension of the spring 25. The movable leaves of the bellows and the cross-bar 21 carried thereby will thus be moved downward a certain distance, thereby swinging the valve 17 to partially close the port 16 and decrease the tension in the chamber 12. The tension thus obtained may be designated "F," full tension being indicated by "FF."

If the tube 43 is thereafter opened the bellows 23 will be connected to the low tension chamber 31 and the movable leaves of 105 the bellows will be moved further downward by the increased relative pressure thereon, thus moving the valve 17 to cover an additional portion of the port 16 and produce a soft tension designated "P." If 110 the tube 44 is thereafter opened the bellows 24 will become operative and the valve 17 will be swung still further downward to more completely close the port 16, giving 115 a very soft or "PP" effect.

120 Referring now to Figs. 4, 5 and 6, I will describe the setting device for automatically opening and closing the tubes 41, 43 and 44. A separate setting device is provided for controlling each of the said tubes, the con- 125

struction and operation of the three setting devices being precisely similar. The tube 41 (Fig. 4.) is connected to a passage 50 formed in a block 51 and normally covered by a valve 52. The valve 52 is secured to the movable leaf 53 of a small pneumatic bellows 54, (Fig. 5) said leaf having an extension 53^a adapted to engage a light spring latch 55 as will be hereinafter described.

10 The pneumatic 54 is connected by a passage 56 (Figs. 4 and 5) to a valve chamber 57 having the same general construction as the valve chamber 33 previously described. A double valve 58 is mounted in the chamber 57 and the head 59 of said valve is positioned for engagement by a diaphragm 60 covering a recess 61 connected to a tube 62. The tube 62 extends to a special opening 63 (Fig. 1) formed in the 15 tracker bar T and normally covered by the note sheet N. The sheet is provided with correspondingly positioned perforations 65 adapted to uncover said opening 63 at predetermined times.

20 25 The diaphragm 60 (Fig. 5) is interposed between the recess 61 and a low tension chamber 66 connected by a passage 67 to the exhaust of the instrument. The usual bleed opening 68 connects the chamber 66 to the recess 61 and equalizes the pressure on the diaphragm 60. When the tracker opening 63 is uncovered the diaphragm 60 will be forced inwardly by atmospheric pressure, carrying with it the valve 58 and thus connecting the pneumatic 54 to the 30 low tension chamber 66. The pneumatic is thus collapsed, opening the passage 50, and thus partially deflating the bellows 22 as previously described.

35 40 As the pneumatic 54 is collapsed the extension 53^a of its leaf 53 will engage the latch 55 and the pneumatic will be thereby maintained in collapsed condition, with the passage 50 and tube 41 open to the atmosphere even after the tracker opening 63 is again covered by the sheet N. I am thus able to continue any indicated tension for any desired time without using either long or often-repeated perforations in the note- 45 sheet, a result of much importance.

The latch 55 is mounted upon a support 70 (Figs. 5 and 6) pivoted at 71^b and adapted to swing outwardly, thus moving the latch out of contact with the extension 53^a and releasing the pneumatic 54.

The support 70 is held yieldingly in position by a spring 70^a (Fig. 6) and is controlled by a pneumatic 71 (Fig. 5) the movable leaf 72 thereof being provided with an 60 arm 73 connected to a sliding rod 74 having its free end positioned to engage a lug or projection 75 secured to the upper edge of the support 70. When the pneumatic 71 is collapsed the rod 74 will slide outwardly 65 and through its engagement with the lug

will swing the support 70 to release the pneumatic 54.

The pneumatic 71 is controlled by a double valve and diaphragm similar to those previously described, the tube 76 connected therewith extending to an opening 77 (Fig. 1) in the tracker bar T. The valve chamber 78 is connected to the pneumatic 71 by a passage 79.

Additional pneumatics 80 and 81 (Fig. 5) 75 control the passages 82 and 83 which are connected with the tubes 43 and 44 respectively. The pneumatics 80 and 81 are controlled by diaphragms or pouches connected by tubes 84 and 85 to openings 86 and 87 80 (Fig. 1) in the tracker bar T.

From this description it will be evident that whenever any one of the openings 63, 86 or 87 is uncovered the corresponding pneumatic 54, 80 or 81 will be deflated, thus 85 connecting one of the bellows 22, 23 or 24 to the low tension chamber and thereby moving the tension valve 17 to close the port 16 to a greater or less extent.

As has been previously described the position of the expression valve 17 is determined by the action of one or more of the bellows 22, 23 and 24, these bellows all acting against the single spring 25. If the tension is to be only slightly decreased (F) 90 the bellows 22 is used. For an additional decrease in tension (P) the bellows 23 is also placed in operation and the bellows 24 is added when an extremely soft expression (PP) is desired. 95

It would be possible to regulate the action of these different bellows separately from the special openings in the tracker bar through the controlling mechanism above described, providing two perforations in the 100 sheet when two bellows are to be rendered operative, and three perforations when an extremely soft effect is desired. I consider it desirable, however, to produce any desired expression by means of a single perforation in the note sheet and in order to obtain this result I provide suitable connections between the pneumatics 54, 80 and 81. 105 110

These connections as shown comprise 115 cords or other flexible members 90 and 91 (Fig. 5), the cord 90 being secured at its opposite ends to the movable leaves of the pneumatics 54 and 80 and the cord 91 being similarly secured to the movable leaves 120 of the pneumatics 80 and 81. If the opening 63 in the tracker bar is now uncovered the pneumatic 54 will be collapsed and will be retained in collapsed position by its latch 55, thus producing a minimum 125 change of position in the tension valve 17.

If, however, the opening 86, instead of the opening 63, is uncovered the pneumatic 80 will be deflated, thus opening the passage 82 which controls the bellows 23 and at 130

the same time it will move the leaf 53 of the pneumatic 54 to uncover the opening 50 which controls the bellows 22. In this manner the bellows 22 and 23 are controlled 5 from the single tracker opening 86.

In a similar way the uncovering of the opening 87 causes deflation of the pneumatic 81, said pneumatic acting through the cords 91 and 90 upon the movable leaves of the 10 pneumatics 80 and 54, thus placing all three bellows 22, 23 and 24 in operation and controlling them through the single tracker opening 87, the latches 55 retaining said pneumatics in operative or deflated condition. 15

If the full force (FF) of the instrument is thereafter desired the opening 77 in the tracker bar will be uncovered, thus deflating the pneumatic 71 and swinging the 20 latch support 70 outward to release the pneumatics 54, 80 and 81 or any of them, from operative position.

It will often happen however, that a change of expression is desired from the 25 extremely soft (PP) expression to an intermediate expression (P or F), and it is desirable to obtain this change of expression from a single perforation in the note sheet. It is necessary therefore that all of the 30 pneumatics should be released whenever any change in expression is indicated. In order to secure this result I provide a cross passage 92 (Fig. 4) which communicates at one end with the passage 79 and which is 35 connected by passages 93, 94 and 95 to the passages 56, etc., leading to the pneumatics 54, 80 and 81 respectively. Flap valves 96, 97, 98 and 99 are provided in the passages 93, 94, 95 and 79, these valves being so arranged that a reduction of pressure in any 40 one of the pneumatics 54, 80 or 81 will cause a corresponding deflation of the pneumatic 71, while at the same time the low pressure in one of the pneumatics 54, 80 or 81 will not 45 affect the other two pneumatics.

Through these connections the releasing pneumatic 71 will become operative whenever any one of the pneumatics 54, 80 or 81 becomes operative. The latches 55 are 50 thus moved to release all of the pneumatics whenever any change in tension is indicated by the note sheet.

It is necessary that the latches after 55 releasing the pneumatics shall be immediately restored to operative position so that they may retain the newly indicated pneumatic or pneumatics in operative position. For this purpose the sliding rod 74 is provided with an oblique or offset portion 74^a (Fig. 5) and is mounted to slide in a slot 100 (Fig. 4) formed in a block 101 mounted upon a fixed portion of the pneumatic 81.

As the releasing pneumatic 71 is deflated the rod 74 slides freely through the slot 100 65 and by engagement with the lug 75 upon the

latch support 70 it swings the support outwardly to release the pneumatics. Excessive accidental displacement of the support is prevented by a stop screw rod 102. The continued movement of the rod 74, however, causes the offset portion 74^a to engage the block 101, the rod being thereby swung to the right, as viewed in Fig. 5, out of engagement with the lug 75. The support 70 is thereupon immediately returned to its operative position by the spring 70^a (Fig. 6). The latches are thus returned to operative position before the setting pneumatics are released by the note sheet and said pneumatics will thus be retained in the position 80 to which they have been or may thereafter be moved.

Having thus described the preferred form of my invention it will be seen that I have provided tension controlling mechanism by 85 which a series of different tensions may be secured and that I have also provided improved automatic devices controlled by perforations in the note sheet by means of which any desired tension may be secured. 90 Furthermore any desired tension may be at any time secured by the provision of a suitable single perforation in the note sheet regardless of the tension previously maintained in the instrument. 95

In Figs. 7, 8, 9, and 10 I have shown a modified form of setting mechanism in which the setting pneumatics are omitted and the tension regulating bellows 22, 23 and 24 are more directly controlled from the openings in the tracker bar. Considering the control of the bellows 22, the tube 41 (Figs. 2 and 3) is connected to a passage 110 (Fig. 9) formed in a frame 111 and communicating with a cross passage 112. At its upper end the cross passage is open to the atmosphere and at its lower end it is open to an exhaust chamber 113 connected by a pipe 113^a (Fig. 10) to the exhaust of the instrument. A double 110 valve 114 is mounted to slide loosely lengthwise of the cross passage 112, closing the passage at one end or the other according to conditions. At its lower end the valve 114 is provided with a head 114^a positioned 115 for engagement by a diaphragm 115 covering a recess 116, connected by a passage 117 to the tube 62 extending to the opening 63 (Fig. 1) in the tracker bar. The usual bleed opening 119 (Fig. 8) connects the recess 116 with the chamber 113 thus providing a normally low pressure on each side of the diaphragm 115. The passage 110 above referred to is provided with an extension 110^a containing a flap valve 120 and communicating with a cross passage 121 (Fig. 7).

Substantially similar valve mechanism is provided for controlling the admission of air through the passages 122 and 123 to the 130

tubes 43 and 44 through which the bellows 23 and 24 are governed, these mechanisms being connected by tubes 84 and 85 to tracker openings 86 and 87 and being also connected to the cross passage 121.

Referring to Fig. 9, the valve 114 is connected at its upper end to a lever 130 having its outer end positioned for engagement by a pawl 131 adapted to retain the valve in raised position.

From the foregoing description the operation of this portion of the mechanism will be clearly evident. When a perforation in the note sheet admits atmospheric pressure through the tube 62 and passage 117 to the recess 116 the diaphragm 115 will be raised, carrying with it the valve 114, thus closing the connection between the passage 110 and the exhaust chamber 113, and at the same time opening the passage 110 to the atmosphere. Since the passage 110 communicates directly with the tube 41, atmospheric pressure will accordingly be transmitted through the tube 41 to the recess 40, as in the preferred form of my invention, thus rendering operative the bellows 22.

At the same time atmospheric pressure will be transmitted through the passage extension 110^a to the cross passage 121. This passage 121 communicates by a transverse passage 132 (Fig. 10) with a recess 133, covered by a diaphragm 134, which controls the release valve 135. The valve 135 is pivotally connected to a lever 136 having a depending latch 137 positioned to engage an arm 138^a fixed to an offset bar 138 (Fig. 7) pivotally supported in bearings 139 secured to the frame 111. The offset portion of the bar extends lengthwise of the device and engages projecting portions 131^a of the pawls 131. Such engagement by the bar 138 moves the pawls 131 rearwardly and permits the levers 130 and the valves 114 connected thereto to return to normal or lowered position.

The latch 137 (Fig. 10) is provided with a laterally extending arm 137^a positioned to engage an adjustable stop 140 as the lever 136 is raised. The stop 140 should be so adjusted that the arm 137^a will engage the stop as soon as the levers 130 have been released. Continued upward movement of the lever 136 will swing the latch 137 to the right (Fig. 10) thus releasing the offset bar 138 and permitting the pawls 131 to return to positions in which they again cooperate with the levers 130. The release valve 135 may also be operated directly from the opening 77 (Fig. 1) in the tracker bar, being connected thereto by the tube 76 as in the preferred form.

As the valves which control the bellows 22, 23 and 24 are each connected to the cross passage 121, the release valve 135 will be

operated whenever any one of the expression valves is moved from normal position.

In order that the operation of two or three of the bellows 22, 23 and 24 may be controlled by a single perforation in the note sheet I have provided additional cross passages, most clearly shown in Fig. 8. A passage 150 is normally closed by the valve 151 and when opened admits atmospheric pressure directly to the passage 110, at the same time that atmospheric pressure is admitted to the passage 122. A similar passage 152 normally covered by the valve 153 when opened admits atmospheric pressure to the tube 122. The valve 153 also covers an additional passage 154 connecting into the passage 150 and thus adapted to admit atmospheric pressure to the tube 110. The raising or opening of the valve 151 thus admits atmospheric pressure to the two bellows 22 and 23 while the raising of the valve 153 admits atmospheric pressure to all three of the bellows 22, 23, and 24.

This modified form of setting device is not specifically claimed herein but forms the subject matter of a divisional application, Serial No. 545,593 filed by me March 21, 1922.

Having thus described my invention it will be seen that other changes and modifications can be made therein by those skilled in the art without departing from the spirit and scope thereof as set forth in the claims, and I do not wish to be otherwise limited to the details herein disclosed. What I do claim is:—

1. An expression device for an automatic musical instrument having a tracker bar and a perforated note sheet, comprising an adjustable air tension regulator, a plurality of sheet-controlled setting devices each effective to adjust said regulator to maintain a different air tension, each setting device being connected to an opening in the tracker bar and being moved to a position in which it renders said regulator operative when said opening is uncovered, means to retain said setting device in such position after said opening is closed, and means to release all of said setting devices whenever the tracker opening leading to any one of said setting devices is thereafter uncovered.

2. An expression device for an automatic musical instrument having a tracker bar and a perforated note sheet, comprising an adjustable air tension regulator, a plurality of sheet-controlled setting devices each effective to adjust said regulator to maintain a different air tension, each setting device being connected to an opening in the tracker bar and being moved to a position in which it renders said regulator operative by the uncovering of said openings, and connections between said devices whereby certain

of said devices when moved to operative position are effective to move additional setting devices to similar positions.

3. An expression device for automatic musical instruments having a tracker bar, and a note-sheet, comprising an air tension regulator, a pneumatic motor connected to adjust said regulator and having a plurality of separate bellows therein, a separate pneumatic for controlling the operation of each bellows, said pneumatics being connected to separate openings in the tracker bar and being controlled by the perforated note sheet, and means independent of the note sheet for retaining said pneumatics in position to render said bellows operative.

4. An expression device for automatic musical instruments having a tracker bar and a note sheet, comprising an air tension regulator, a pneumatic motor connected to adjust said regulator and having a plurality of separate bellows therein, a separate pneumatic for controlling the operation of each bellows, said pneumatics being connected to separate openings in the tracker bar and being controlled by the perforated note sheet, means independent of the note sheet for retaining said pneumatics in position to render said bellows operative, and sheet-controlled means for releasing said pneumatics.

5. An expression device for automatic musical instruments having a tracker bar and note sheet, comprising an air tension regulator, a pneumatic motor connected to adjust said regulator and having a plurality of separate bellows therein, a separate pneumatic for controlling the operation of each bellows, said pneumatics being connected to separate openings in the tracker bar and being controlled by the perforated note sheet, means to retain said pneumatics in position to render said regulator operative, a releasing pneumatic connected to a separate opening in the tracker bar, and a device actuated by said pneumatic when said opening is uncovered and effective when so actuated to release all of the other pneumatics which are thus retained out of normal position.

6. An expression device for automatic musical instruments having a tracker bar and note sheet, comprising an air tension regulator, a pneumatic motor connected to adjust said regulator and having a plurality of separate bellows therein, a separate pneumatic for controlling the operation of each bellows, said pneumatics being connected to separate openings in the tracker bar and being controlled by the perforated note sheet, means to retain said pneumatics in position to render said regulator operative, a releasing pneumatic connected to a separate opening in the tracker bar and to each of the first men-

tioned openings, and a device actuated by said pneumatic whenever any one of said openings is uncovered and effective when so actuated to release all of the pneumatics which are thus retained out of normal position. 70

7. An expression device for automatic musical instruments having a tracker bar and note sheet, comprising an air tension regulator, a pneumatic motor connected to adjust said regulator and having a plurality of separate bellows therein, a separate pneumatic for controlling the operation of each bellows, said pneumatics being connected to separate openings in the tracker bar and being controlled by the perforated note sheet, and connections between said pneumatics whereby certain of said pneumatics when moved to render said regulator operative will also move additional pneumatics to similar 80 positions. 85

8. An expression device for automatic musical instruments having a tracker bar and note sheet, comprising an air tension regulator, a pneumatic motor connected to adjust said regulator and having a plurality of separate bellows therein, a separate pneumatic for controlling the operation of each bellows, said pneumatics being connected to separate openings in the tracker bar and being controlled by the perforated note sheet, and connections between said pneumatics whereby certain of said pneumatics when moved to render said regulator operative will also move additional pneumatics to similar 90 positions, said connections being operative in one direction only. 95

9. An expression device for automatic musical instruments having a tracker bar and note sheet, comprising an air tension regulator, a pneumatic motor connected to adjust said regulator and having a plurality of separate bellows therein, a separate pneumatic for controlling the operation of each bellows, said pneumatics being connected to 100 separate openings in the tracker bar and being controlled by the perforated note sheet, and flexible connections between said pneumatics whereby certain of said pneumatics when moved to render said regulator operative 110 will also move additional pneumatics to similar 115 positions.

10. An expression device for an automatic instrument having a tracker bar and perforated note-sheet, comprising an adjustable air tension regulator, a plurality of sheet-controlled setting devices each effective to adjust said regulator to maintain a different air tension, a separate latch to hold each setting device out of normal position, and a 120 single automatically controlled device effective to move all of said latches to release the setting device held thereby. 125

11. An expression device for automatic musical instruments having a tracker bar and 130

note sheet, comprising an air tension regulator, a pneumatic motor connected to adjust said regulator and having a plurality of separate bellows therein, a separate pneumatic for controlling the operation of each bellows, said pneumatics being connected to separate openings in the tracker bar and being controlled by the perforated note sheet, a latch to hold each pneumatic when moved to render said regulator operative, and a single additional sheet-controlled pneumatic effective to move all of said latches to release the pneumatics held thereby.

12. An expression device for automatic musical instruments having a tracker bar and note sheet, comprising an air tension regulator, a pneumatic motor connected to adjust said regulator and having a plurality of separate bellows therein, a separate pneumatic for controlling the operation of each bellows, said pneumatics being connected to separate openings in the tracker bar and being controlled by the perforated note sheet, a latch to hold each pneumatic when moved to ren-

der said regulator operative, a support for all of said latches and means to move said support to simultaneously release all of said pneumatics which are out of normal position.

13. An expression device for automatic musical instruments having a tracker bar and note sheet, comprising an air tension regulator, a pneumatic motor connected to adjust said regulator and having a plurality of separate bellows therein, a separate pneumatic for controlling the operation of each bellows, said pneumatics being connected to separate openings in the tracker bar and being controlled by the perforated note sheet, and connections between said pneumatics whereby certain tracker openings are rendered effective to control a plurality of pneumatics.

In testimony whereof I have hereunto set my hand.

THOMAS DANQUARD.
